(54) **SPINNING & TWISTING STRAW, HAY, &C.**

(76) Inventor: **Philo G. Sheldon**

Philo G. Sheldon
Letters Patent

The schedule referred to in these Letters Patent and making part of the same containing a description in the words of the said Philo G. Sheldon himself of his improvement in the mode of spinning or twisting straw, hay or other substances

To all whom it may concern. Be it known that I Philo G. Sheldon of Winchester in the County of Litchfield and State of Connecticut have invented a new and improved mode of twisting or spinning hay, straw, straw, or any similar material & in the form of twist or rope for packing or doing up scythes or other articles of hand work or for any other purpose to which such twist or rope may be applied & I do hereby declare that the following is a full & exact description of the apparatus or machinery which I employ for that purpose. I make a spindle which is furnished with flyers & a spool or drum much in the form of the spinster flyers & bobbins used in the spinning of hemp, cotton or other fibrous materials but so modified in size & form that the nature of certain of its appendages as to adapt them to the special purpose to which I apply it & for which it has not heretofore been employed. I form a spindle of wood or metal but most generally of iron which may be ten feet in length more or less. this however is in practice I have found a good length. This spindle I place horizontally supporting it upon proper bearings or boxes near its ends. The spindle is hollow at its head or has an eye or opening through which the material to be spun is to pass in a manner common to such spinners. Just below the latter at opening from the said hollow end arms project out on opposite sides & are so wrought as to form large flyers adapted to the spindle. which flyers may also be made of wood or of metal or of the two combined to get them to sustain them I usually penile their extreme ends by a crosspiece extending from one to the other. Upon the spindle & within the flyers I place a bobbin or drum with suitable heads to receive the spun material as it is delivered from the flyers & to said spool I apply a friction pulley

by with a band & weights or employ other well known means to control & regulate its motion. Upon one rim or side of the flyers place two or more pulleys or hooks upon which to place the rope while it is being spun or twisted so as to conduct it on to its proper place on the drum or post; when two only are employed that which conducts it on the post or drum must be made to slide or shift along the whole length thereof, & both or other contrivance is used to attach the rope to the drum in the first instance when the spinning is commenced. Motion may be given to the spindle by means of a wheel & band, or otherwise. What I claim as my invention is the adaptation of a spindle with its appendages as herein described to the purpose and in the manner set forth. I claim nothing more, the general principle of its action being similar to that in other spinning apparatus.
